BULLDOZER

Albert E. Blomquist, Ringoes, N.J., assignor to Fairchild Engine and Airplane Corporation, Hagerstown, Md., a corporation of Maryland

Application September 3, 1954, Serial No. 454,076

9 Claims. (Cl. 37—117.5)

This invention relates to bulldozers and relates especially to improvements in bulldozer blades and mounting means therefor for attachment in front of a propelling vehicle.

In a bulldozer, better and more effective operation is made possible when the inertia is due to the bulldozer blade itself rather than the vehicle. However, massiveness and great weight during transportation of a bulldozer to a place of intended use are in any case a decided disadvantage.

It is an object of this invention to provide construction for a bulldozer blade and means for mounting the bulldozer blade in front of a propelling vehicle whereby a bulldozer blade may have imparted thereto a maximum amount of steadiness and effective inertia in relation to the size and weight of the parts.

It is a feature of this invention that the mounting means for a bulldozer blade whereby it is adjustably carried in front of a propelling vehicle is such that the force applied to the back of the bulldozer blade for both pushing it forward and providing inertia thereto is distributed and applied so as to provide maximum stability and effectiveness in the use of the bulldozer blade. To this end both the inertia of the vehicle and the inertia of a ballast compartment are transmitted to the bulldozer blade adjacent both the upper margin thereof and the lower margin thereof.

A more particular aspect and feature of this invention resides in the combination with the bulldozer blade of a ballast compartment which is secured directly to the back of the bulldozer blade by suitable securing means which preferably is such that the ballast compartment is secured to the back of the bulldozer blade both adjacent the upper margin of the bulldozer blade and adjacent the lower margin of the bulldozer blade. In preferred construction the side walls and bottom of the ballast compartment are rigidly secured to the back of the bulldozer blade and the forward wall of the ballast compartment is provided by a portion of the bulldozer blade itself. By securing the ballast compartment directly to the back of the bulldozer blade the entire weight of the compartment as well as the ballast contained therein is effective at the bulldozer blade for preventing the bulldozer blade from being displaced in any direction.

A further feature of this invention resides in the provision of means whereby a ballast compartment which is secured to the back of the bulldozer blade may be automatically filled. As will be described more in detail hereinbelow, this has been preferably accomplished by providing an opening in the bulldozer blade itself in the region where the ballast compartment is secured to the back thereof and by providing a closure for the opening so that when the closure has been opened forward propulsion of the bulldozer blade in the usual way will automatically fill the ballast compartment from in front of the bulldozer blade and through the opening therein.

Another feature of this invention resides in the fact that the inertia of the vehicle is transmitted directly to

2

the bulldozer blade so as to be effectively applied both adjacent the upper margin thereof and adjacent the lower margin thereof by horizontally disposed extensible arm means hingedly secured to the blade and to the vehicle 5 for angular movement in a vertical plane relative to said blade and said vehicle, respectively, there being brace means disposed in a vertical angle relative to the arm means and power actuated means comprised in the arm means whereby desired positioning of the bulldozer blade 10 during use may be effected. The term "horizontally disposed" is used in a broad sense as inclusive of substantial departures from the true horizontal such as are incident to raising and lowering the forward ends of the bar means for the purpose of adjusting the position of 15 the bulldozer blade.

It is also a feature of this invention that the inertia of the vehicle as transmitted to the bulldozer blade adjacent the upper and lower margins thereof has a cumulative effect in conjunction with the manner of application 20 of the inertia supplied by the ballast in the ballast container which is secured to the back of the bulldozer blade.

While the features of this invention are preferably employed in combination in order to afford the enhanced benefits and utility which result from such combination, 25 certain features of this invention may be practiced separately.

Further objects, features and advantages of this invention are apparent from the following description of certain embodiments of this invention which have been 30 shown for illustrative purposes in the accompanying drawings, wherein:

Fig. 1 is a side elevation of the front portion of a bulldozer vehicle showing the bulldozer blade and mounting means therefor of this invention mounted on the front 35 end of a propelling vehicle;

Fig. 2 is a plan view of the bulldozer shown in Fig. 1, only one-half being shown since the other half is the complement of that shown;

Fig. 3 is a front view on a smaller scale of the bulldozer shown in Figs. 1 and 2; and

Fig. 4 is a side elevation similar to Fig. 1 with the bulldozer blade and ballast compartment shown in section along the center line constituting the upper margin of Fig. 2.

45 In the drawings the propelling vehicle is indicated generally by the reference character 10 and comprises the body 11 which is carried on the wheels 12. The vehicle may be provided with a cab 13 where the operator and the controls used by the operator may be conveniently located. Suitable means (not shown) may be used for 50 supplying power to the wheels 12 for propelling the vehicle in either direction. While a vehicle has been shown of the type comprising large wheels on which a pneumatic tire may be placed, it is apparent that any other type of 55 means for carrying and propelling the vehicle body 11 may be employed, e.g., endless treads.

The bulldozer blade is indicated generally by the reference character 14. Extending rearwardly therefrom is the ballast container which is indicated generally by the 60 reference character 15. In the embodiment shown the ballast container comprises the side walls 16, the bottom 17 and the rear wall 18 which is integral with the side wall 16 and with the bottom 17. The side wall 16 and the bottom 17 contact the back of the bulldozer blade in conformity therewith and are rigidly secured to the back 65 of the bulldozer blade 14 as by welding. The forward portion of the ballast container is provided by the portion of the bulldozer blade which lies in front of where the side walls 16 and the bottom 17 of the ballast compartment are rigidly secured thereto.

70 For admitting ballast into the ballast container 15 as well as jettisoning ballast therefrom the portion of the

bulldozer blade which constitutes the forward wall of the ballast compartment has an opening therein over which there is disposed the closure or door 19. The closure 19 is hingedly secured to the portion of the bulldozer blade adjacent the upper margin thereof by the hinges 20 which permit the closure 19 to be swung outwardly and upwardly to the position shown in dotted lines in Fig. 4. It is preferable that the closure 19 be provided with power actuated means for opening and closing it. In the embodiment shown such power actuated means consists in the curved arm 21 which is rigidly secured to the inner surface of the closure 19 and which is pivotally secured at the hinge 22 to the end of a piston 23 that operates within the hydraulic cylinder 24, the hydraulic cylinder 24 being pivotally secured at the hinge 25 to the lug 26 that is attached to the rear wall 18 of the ballast container. For simplicity and clarity in the drawings hydraulic lines leading to the cylinder 24 for actuating the piston 23 in either direction have not been shown inasmuch as such lines and means for controlling hydraulic pressure therein are conventional and well known. For like reasons the hydraulic lines leading to the cylinders 32 and 38, to be described below, have not been shown.

It is believed to be evident from the description thus far that even though the bulldozer blade 14 may be made of relatively light gauge metal the ballast compartment 15 when filled with ballast increases the inertia of the bulldozer blade many times. Moreover, since the ballast compartment 15 is distributed so that its securement to the back of the bulldozer blade comes adjacent both the upper margin and the lower margin of the bulldozer blade, the inertia effect of the ballast is evenly distributed so as to enable lighter gauge metal to be used both in the bulldozer blade itself and in the mounting means therefor, for regardless of where shocks and strains may be localized on the front of the bulldozer blade, the counteracting effect of the inertia supplied by the ballast is effective with a minimum amount of misalignment of opposing forces. Moreover, since the ballast compartment is secured directly to the back of the bulldozer blade the inertia effect in resisting both vertical movements and horizontal movements is at the bulldozer blade itself where it is of maximum effectiveness.

When it is desired to fill the ballast compartment all the operator has to do is to operate the hydraulic cylinder 24 so as to swing the door 19 outwardly and upwardly to the position shown in dotted lines in Fig. 4. After this has been done the vehicle can be propelled to push the bulldozer blade 14 into a mass of earth and force the earth into the ballast compartment 15. Upon then operating the hydraulic cylinder 24 to effect the closing of the door 19 the ballast will be effectively contained and retained in the ballast compartment 15 to supply the inertia to the bulldozer blade in the manner and with the advantages aforesaid. After the work has been finished it is a very simple matter upon opening the door 19 to permit the dumping of the ballast so as to restore the parts to the light-weight condition that is desirable for transportation.

While the means for opening and closing the closure 19 has been described hereinabove as though there were only a single hydraulic cylinder 24 and associated parts, as shown in Fig. 2, it is to be understood that the cylinder 24 and the parts associated therewith are duplicated. Moreover, if desired, more than two such cylinders may be used. These comments apply to the structural elements to be described hereinbelow which are comprised in the mounting means whereby the bulldozer blade 14 is mounted in front of the propelling vehicle 10.

The mounting means of this invention for mounting the bulldozer blade in front of the propelling vehicle has been exemplified in the drawings as comprising upper arm means, which is indicated generally by the reference character 27, and lower arm means, which is indicated generally by the reference character 28, for connecting the bulldozer blade to the vehicle in adjustable relation

thereto. The upper arm means 27 comprises the piston member 29 which is pivotally connected by the hinge 30 to the hinge part 31 that is secured to the bulldozer blade 14 adjacent the upper margin thereof, as by welding. The upper arm means 27 also comprises the hydraulic cylinder 32 which is pivotally secured to the vehicle body 11 by the hinge 33 which comprises the hinge part 34 that is secured as by riveting to the vehicle body 11. The hinges 30 and 33 are such that the arm means 27 is mounted for angular movement in a substantially vertical plane in relation both to the bulldozer blade 14 and the vehicle body 11.

The lower arm means 28 is similar to the upper arm means 27 and comprises the piston member 35 which is connected by the hinge 36 to the hinge part 37 that is secured to the bulldozer blade adjacent the lower margin thereof. The lower arm means 28 also comprises the hydraulic cylinder 38 which is connected by the hinge 39 to the hinge part 40 that is secured to the vehicle body 11. The hinges 36 and 39 are such as to provide angular movement in a vertical plane of the arm means 28 relative to the bulldozer blade 14 and the vehicle body 11. In order that the angle in a horizontal plane that the arm means 28 makes with the bulldozer blade 14 and the vehicle body 11 also may be varied, the hinges 36 and 39 are of the universal type for permitting such angular movement in the horizontal plane as well as in a vertical plane.

Since the upper arm means 27 and the lower arm means 28 are substantially horizontally disposed in substantially parallel horizontally disposed planes and are hingedly secured in the manner described both to the bulldozer blade 14 and to the vehicle body 11, additional brace means is required for holding up the bulldozer blade. In the embodiment shown this additional brace means consists of the strut 41 which is connected by a universal type hinge 42 to the hinge part 43 which is secured to the bulldozer blade adjacent the upper margin thereof. The strut 41 extends diagonally downwardly so as to be connected by a universal type hinge 44 which comprises the hinge part 45 that is secured to the vehicle body 11 at a level which is adjacent that at which the lower arm means 28 is secured to the vehicle body 11. By virtue of the angular relationship between the strut 41 and the upper and lower arm means 27 and 28 respectively the bulldozer blade 14 is supported in front of the vehicle body 11. The hydraulic cylinder 32 in the arm means 27 and the hydraulic cylinder 38 in the arm means 28 are operable for longitudinally extending and contracting the arm means 27 and 28 either together or selectively, as may be desired, for controlling the position of the bulldozer blade 14. For example, by extending the upper arm means 27 to the position shown in dotted lines in Fig. 1 the position of the bulldozer blade is changed to the lowered position shown in dotted lines in Fig. 1. If it should be desired that the bulldozer blade 14 in the lowered position shown in dotted lines in Fig. 1 remain at essentially the same inclination shown in solid lines, then the hydraulic cylinder 38 in the lower arm means 28 can likewise be actuated to extend the longitudinal length of the lower arm means to likewise bring forward the lower margin of the bulldozer blade. Conversely by contracting the length of the upper arm means the bulldozer blade can be elevated. Thus, the upper and lower arm means provide means whereby the bulldozer blade may be held in a substantially vertical plane, and these arm means in combination with the strut means 41 provide power activated means for elevating and lowering the forward ends of the arm means relative to the vehicle.

While the forward end of the upper and lower arm means 27 and 28 may be raised and lowered for the purpose of adjusting the position of a bulldozer blade, each of these arm means is to be regarded as being horizontally disposed for they are adapted, when in at least one angular position, to be substantially horizontal and likewise are disposed in the at least approximately horizontal

line of thrust imposed by a mass of earth in front of the bulldozer blade in the direction of the vehicle body during forward propulsion of the vehicle. It is to be noted that these horizontally directed lines of thrust are directly applied from the vehicle to the bulldozer blade adjacent both the upper and the lower margins thereof so as to provide positive support backed by the inertia of the vehicle for resisting shocks imposed, whether the shocks are exerted adjacent the upper margin of the bulldozer blade or adjacent the lower margin. Thus much more effective use of the inertia of the vehicle is afforded and the bulldozer blade is held in such way as to be more resistant to displacement by shocks and so as to have greater strength for the thickness and weight of the metal used in the bulldozer blade and mounting means therefor.

While this invention has been described in connection with the specific embodiments thereof shown in the accompanying drawings, it is to be understood that this has been done for illustrative purposes and that the structure shown may be modified without departing from the principles utilized according to this invention as hereinabove described and exemplified. Thus while preferred means for automatically filling the ballast compartment have been shown, the ballast compartment could, if desired, be filled and emptied by hand or a clean-out door could be provided in the bottom thereof. Similarly, the mounting means for the bulldozer blade may be varied without departing from the scope of this invention. Thus the brace means which has been shown as comprising the strut 41 could be varied by replacing the strut 41 with a member having some other vertical angular relation with respect to the arm means 27 and 28 for coaction with these arm means in providing support for the bulldozer blade. For example, the member 41 could be disposed angularly in the other direction with respect to the arm means 27 and 28, i.e., with the forward end lowermost, so as to serve as a tie bar for securing to the bulldozer blade adjacent the lower margin thereof and securing to the vehicle body at an elevation which is adjacent that of the hinge means by which the upper arm means is hingedly secured to the vehicle body 11.

I claim:

1. A bulldozer comprising in combination a bulldozer blade, a propelling vehicle, a ballast compartment, means for rigidly securing said ballast compartment to the back of said bulldozer blade adjacent the upper margin of said bulldozer blade and adjacent the lower margin of said bulldozer blade, and mounting means for mounting said bulldozer blade in front of said vehicle, said mounting means comprising first horizontally disposed extensible arm means hingedly secured adjacent one end thereof to said bulldozer blade adjacent the upper margin thereof and adjacent the other end thereof to said vehicle for angular movement of said first arm means relative to said blade and to said vehicle in a substantially vertical plane, second horizontally disposed extensible arm means hingedly secured adjacent one end thereof to said bulldozer blade adjacent the lower margin thereof and adjacent the other end thereof to said vehicle for angular movement of said second arm means relative to said blade and to said vehicle in a substantially vertical plane, power actuated means comprised in said first arm means for longitudinally extending and contracting said first arm means, power actuated means comprised in said second arm means for longitudinally extending and contracting said second arm means, and brace means hingedly secured adjacent one end thereof to said blade and adjacent the other end thereof to said vehicle for angular movement relative to said blade and to said vehicle in a substantially vertical plane, said brace means being disposed in vertical angular relation with respect to said first and second arm means for coaction therewith in supporting said blade in front of said vehicle.

2. A bulldozer comprising in combination a bulldozer

blade, a propelling vehicle, a ballast compartment, securing means for rigidly securing said ballast compartment directly to the back of said blade adjacent the upper margin of said blade and adjacent the lower margin of said blade, said bulldozer blade having an opening therein communicating with the interior of said ballast compartment from the front of said bulldozer blade, a closure for said opening hingedly mounted from above to said blade for swinging outwardly and upwardly, power actuated means for opening and closing said closure, first horizontally disposed extensible arm means hingedly secured adjacent one end thereof to said bulldozer blade adjacent the upper margin thereof and adjacent the other end thereof to said vehicle for angular movement of said first arm means relative to said blade and to said vehicle in a substantially vertical plane, second horizontally disposed extensible arm means hingedly secured adjacent one end thereof to said blade adjacent the lower margin thereof and adjacent the other end thereof to said vehicle for angular movement of said second arm means relative to said blade and to said vehicle in a substantially vertical plane, power actuated means comprised in said first arm means for longitudinally extending and contracting said first arm means, power actuated means comprised in said second arm means for longitudinally extending and contracting said second arm means, and strut means hingedly secured to said bulldozer blade adjacent the upper margin thereof for angular movement in a substantially vertical plane and hingedly secured adjacent the other end thereof to said vehicle at a level adjacent the level at which said second arm means is hingedly secured to said vehicle for angular movement relative to said vehicle in a substantially vertical plane.

3. A bulldozer comprising a bulldozer blade, a propelling vehicle, and mounting means for mounting said blade in front of said vehicle, said mounting means comprising first horizontally disposed extensible arm means hingedly secured adjacent one end thereof to said blade adjacent the upper margin thereof and adjacent the other end thereof to said vehicle for angular movement of said first arm means relative to said blade and to said vehicle in a substantially vertical plane, second horizontally disposed extensible arm means hingedly secured adjacent one end thereof to said blade adjacent the lower margin thereof and adjacent the other end thereof to said vehicle for angular movement of said second arm means relative to said blade and to said vehicle in a substantially vertical plane, power actuated means comprised in said first arm means for longitudinally extending and contracting said first arm means, power actuated means comprised in said second arm means for longitudinally extending and contracting said second arm means, and brace means hingedly secured adjacent one end thereof to said blade and adjacent the other end thereof to said vehicle for angular movement relative to said blade and to said vehicle in a substantially vertical plane, said brace means being disposed in vertical angular relation with respect to said first and second arm means for coaction therewith in supporting said blade in front of said vehicle.

4. A bulldozer comprising a bulldozer blade, a propelling vehicle and mounting means for mounting said blade in front of said vehicle, said mounting means comprising first horizontally disposed extensible arm means hingedly secured adjacent one end thereof to said blade adjacent the upper margin thereof and adjacent the other end thereof to said vehicle for angular movement of said arm means relative to said blade and to said vehicle in a substantially vertical plane, second horizontally disposed extensible arm means hingedly secured adjacent one end thereof to said blade adjacent the lower margin thereof and adjacent the other end thereof to said vehicle for angular movement of said second arm means relative to said blade and to said vehicle in a substantially vertical plane, power actuated means comprised in said first arm means for longitudinally extending and contracting said

first arm means, power actuated means comprised in said second arm means for longitudinally extending and contracting said second arm means, and strut means hingedly secured to said blade adjacent the upper margin thereof for angular movement in a substantially vertical plane and adjacent the other end thereof hingedly secured to said vehicle at a level adjacent the level at which said second arm means is hingedly secured to said vehicle for angular movement relative to said vehicle in a substantially vertical plane.

5. A bulldozer blade having in combination therewith a ballast compartment extending rearwardly from the back of said blade and secured to the back of said blade adjacent the top and bottom margins of said blade, said compartment having a hinged closure member comprised in the forward portion thereof adapted to be moved between open position adapted for ingress of ballast into said compartment responsive to forward propulsion of said blade and closed position adapted to retain ballast therein when said blade is used for moving earth.

6. A bulldozer blade having in combination therewith a ballast compartment which is secured to the back of said blade and the forward wall of which is constituted by a portion of said bulldozer blade, said portion of said bulldozer blade constituting the forward wall of said ballast compartment having a ballast receiving opening therein for reception of ballast through said opening from in front of said bulldozer blade into said compartment, and a closure for said opening hingedly mounted from above for swinging outwardly and upwardly, and power 30 actuated means for opening and closing said closure.

7. A bulldozer comprising in combination a bulldozer blade, a propelling vehicle, horizontally disposed arm means projecting forwardly from said vehicle, said arm means being hingedly secured adjacent the forward end 35 thereof to said bulldozer blade and hingedly secured adjacent the other end thereof to said vehicle for angular movement of said arm means relative to said blade and to said vehicle in a substantially vertical plane, means for holding said blade in a vertically disposed plane, power actuated means for elevating and lowering the forward end of said arm means relative to said vehicle, and a ballast compartment rigidly secured directly to the back 40 of said blade.

8. A bulldozer according to claim 7 wherein said bulldozer blade has an opening therein communicating with the interior of said ballast compartment adapted for ingress of ballast into said compartment responsive to forward propulsion of said blade by said vehicle, and which comprises a removable closure for said opening adapted when in position for closing said opening to retain ballast in said compartment and to prevent ingress of earth through said opening into said compartment when said blade is used for moving earth.

9. A bulldozer comprising a propelling vehicle, a bulldozer blade, mounting means comprising arms secured at their forward ends directly to a first portion of said bulldozer blade and at their rearward ends to said vehicle 15 for mounting said bulldozer blade in front of said vehicle in adjustable relation therewith, a ballast compartment immediately back of said blade which is carried by said first portion of said bulldozer blade in rigidly secured relation therewith and the forward wall of which is provided primarily by a second portion of said bulldozer blade, and means for mounting said second portion of said bulldozer blade for movement relative to said first portion of said bulldozer blade between a position 20 providing a charging opening through said blade for charging ballast into said ballast compartment responsive to forward propulsion of said blade and a position closing said opening and retaining ballast in said compartment when said blade is used for moving earth.
